WELLINGTON W. MUIR, OF BALTIMORE, MARYLAND, ASSIGNOR TO MUIR COMPANY,
INCORPORATED, OF BALTIMORE, MARYLAND, A CORPORATION OF DELAWARE.

CARBURETER.

1,078,591.

Specification of Letters Patent. Patented Nov. 11, 1913.

Application filed February 19, 1913. Serial No. 749,381.

To all whom it may concern:

Be it known that I, WELLINGTON W. MUIR, a citizen of the United States of America, residing at the city of Baltimore, State of Maryland, have invented certain new and useful Improvements in Carbureters, of which the following is a specification.

This invention relates to carbureters and particularly to a float feed carbureter of the aspirating type.

The carbureter art is one which is developed to the highest degree. However, though it can be safely said at this time that no feature of construction or principle of operation which is broadly new in theory is apt to be generally adopted, it is conceded that no carbureter now in use produces perfect results, *i. e.*, that it supplies under all speeds and circumstances a mixture, the proportions of which are such as to give the highest efficiency. It will thus be apparent that if a carbureter is to be produced which gives the most efficient mixture with corresponding economy under all conditions, this must be accomplished by a new combination of features most of which, theoretically at least, and broadly considered, are individually old, and possibly by a mere refinement of detail or by new combinations of minor features or details, and the importance and scope of the invention exercised in the production of such improved device can only be gaged by the result attained.

The carbureter which is the subject of this invention is found to give improved results, and it is believed that the applicant has succeeded in evolving a carbureter which in its normal operation, gives automatically at each speed of the engine and position of the throttle, the mixture best adapted to the engine to which it is applied. Under these circumstances, the engine must, of necessity, develop greater power than hitherto, and operate with increased economy. The desired result is obtained by means of a carbureter having a main air inlet and an auxiliary air inlet, the latter being controlled by means of a valve opened by the suction and a resilient member which tends to maintain the valve closed. A fuel nozzle is placed in the constant air inlet and a fuel valve is provided for controlling the opening at the nozzle, the position of which

valve at all times corresponds exactly to that of and is controlled by the auxiliary air valve.

Referring more specifically to the device in question, the resilient member which tends to close the auxiliary air valve is a constant tension, non-adjustable spring within the carbureter and out of reach of the operator, and the connection between the auxiliary air valve and the fuel valve is accomplished by means of a cam and follower, one being rigidly connected to the air valve and the other mounted on the fuel valve, a spring or other convenient means, as the force of gravity, being utilized to keep the follower in contact with the cam, and the cam itself which is preferably on the auxiliary air valve spindle fixed as to its outline and rigidly and non-adjustably secured to the spindle, is so placed and constructed that it may be, and in fact is, in the case of each engine to which the carbureter is applied, formed to give at each particular instant the mixture with which the engine in question will operate most efficiently under the conditions to which it is then subjected.

This is preferably determined by tests for each type of engine. It is further important that the needle valve or fuel valve is so constructed that its length is adjustable, the purpose of adjusting the length of the needle being to provide for the change of the available fuel supply relatively to the auxiliary air valve opening, as weather conditions or the volatility of the fuel vary.

The adjustment of the needle which is provided makes it possible to change the length of the needle without in any way disturbing the relation of the needle or fuel valve to the auxiliary air valve, and as has been stated, it is extremely important that this relation is such that the motions of the two valves correspond exactly and there is no play or lost motion. As the opening of the auxiliary valve is controlled by a spring and is proportionate to the suction, and the opening of the fuel valve is exactly in proportion to the opening of the auxiliary air valve, which itself is controlled by a constant tension, non-adjustable spring, it will be apparent that the proportions of the mixture under all circumstances are predetermined with any desired degree of precision by the outline of the cam. The adjustment of the needle is preferably limited to the ex-

plosive range of the fuel, so that it is impossible for the adjustment of the carbureter to be so changed by misadjustment that the engine will not run.

In the accompanying drawings, a carbureter is illustrated which embodies the important features of my invention in the preferred form.

Figure 1 is a vertical central section taken on the line of the auxiliary air valve spindle. Fig. 2 is a vertical central section taken at right angles to Fig. 1. Fig. 3 is a plan of the device. Fig. 4 is a section through the fuel valve adjusting screw head and plug, taken at right angles to the axis showing the ball and groove detent.

Referring to the drawings by numerals, each of which is used to indicate the same or equivalent parts in the different figures of the drawing, the carbureter as shown is formed with a casing 1 consisting of a float chamber 2 and a mixing chamber 3. The latter has a constant air inlet 4 which in the preferred form of the device and as shown extends upward through the center of the float chamber, being constricted at 5 where the fuel nozzle 6 is placed. The latter is formed with a passage 7 which leads from the float chamber. The mixing chamber 3 in addition to the constant air inlet, has an auxiliary air inlet 8 closed by an auxiliary air valve 9 opening inward, *i.e.*, in the direction of the suction, and secured to a spindle 10 mounted in suitable bearings 11 and 12, the bearing 11 being preferably supported on the valve seat member 13 and centrally of the valve opening. A constant tension spring 14 shown as encircling the valve spindle and bearing against a suitable abutment 15, acts against the suction and tends to maintain the valve 9 closed. In addition to the openings described, the mixing chamber 3 is provided with an outlet or throttle opening 16 leading to the engine which as shown is controlled by a butterfly valve 17 or other suitable device actuated by the usual throttle lever 18.

In connection with the preferred embodiment of the invention, I have illustrated a spring release for the auxiliary valve. However, the carbureter may be operated without this feature.

The spring abutment 15 is supported on arms 19 secured to a transverse shaft or rotating pin 20 having bearings in the walls of the chamber. This shaft 20 is provided with a follower arm 21 which, as shown, is engaged by a cam 22 on the pivot pin or shaft 23 of the throttle valve 17. It will thus be apparent that in the form of the carbureter shown, as the throttle valve is opened, the tension of the auxiliary valve spring is released, but this is not essential to the operation of the other features of the device as herein described.

The valve spindle 10 is, as I have stated, mounted to slide in alined bearings 11 and 12 in the carbureter chamber, and the casing is so formed that the bearing opening 12 is prolonged or extended to a considerable degree. The fuel nozzle 6 which I have described is controlled by means of a needle valve 25 which is in alinement with the nozzle, both members being, as shown, inclined upward and outward at an angle of about 45°, but the exact arrangement being immaterial, the fuel valve spindle 26 being seated in an aperture 27 which intersects the prolonged bearing aperture 12 to which I have referred. The valve spindle 26 is in fact slotted at 28 in alinement with the aperture 12, and the valve stem 10 and the valve spindle 6 are provided with coöperating cam members. Preferably there is a cam 29 fixed as to its outline and rigidly secured to the valve spindle 10 of the auxiliary valve and adapted to slide back and forth in the outer end of the aperture 12 and through the slot 28; and on the needle valve spindle, secured thereto but adjustable to a slight degree, is the other cam member, shown as a follower 30 to engage and coöperate with the cam member 29. The motion of the valve 9 is limited in this instance by the end of the valve spindle adjacent the cam 29 which in the tixereme position of the valve engages the remote end 43 of the cam aperture.

In order that the needle may be adjusted as to its effective length to vary the opening of the fuel valve in proportion to that of the auxiliary air valve, the needle valve spindle is formed in several parts to be described. These consist of a section of tube 31 mounted to slide in the aperture 27 and pierced by the slot 28 already described. At its lower end, the tube is closed by a plug 32 which is pressed into the end of the tube. This plug carries the needle proper 25 already referred to. The upper end of the tube is closed by means of a plug 33 centrally apertured to receive an adjusting screw 34. This plug is also pressed into the tube and its upper end, which is enlarged, is provided with a socket 35 to receive the head of the adjusting screw. Preferably the screw head is apertured transversely at 36' to receive a spring 36" and a ball 36 which is spring-pressed outwardly, and the inner face of the socket is provided with grooves 37 parallel to the axis and adapted to be enlarged by the ball to lock the screw in adjusted position. The tube thus closed at the ends has a central chamber or barrel 38 in which a cylindrical block 39 is mounted to slide. This block is pierced by the slot 28 to which I have referred and carries the follower 30 previously described, and by moving this block up and down the barrel 38, the effective length of the needle *i.e.*, the dis-

tance from the follower 30 to the seating surface 40 of the needle valve, is varied and adjusted. As I have stated, the block 39 has a sliding fit in the barrel 38 and is 5 of course of a length slightly less than that of the barrel, *i. e.*, the distance between the plugs 32 and 33, and the block 39 is forced upward against the adjusting screw 34 by means of a comparatively stiff spiral spring 41. In the device shown the needle valve 10 is lifted, *i. e.*, the follower 30 is maintained in contact with the cam 29 by means of a comparatively flexible spring 42, the tension of this spring being less than that of 15 the spring 41 so that the latter is not affected by the action of the spring 42. However, the relations of the spring 42 and the cam 29 may be changed in an obvious manner, and the various equivalent structures 20 may be substituted within the scope of the invention.

By observation of the structure shown, it will be apparent that the needle valve in its present adjustment as shown, has its 25 greatest length, *i. e.*, the effective distance between the follower 30 and the seating surface 40 is at its maximum, the sliding block 39 being in its highest position, *i. e.*, resting against the upper plug 33, and it 30 will also be apparent that the screw 34 at its lower end is just in contact with the top of the plug, and the bottom face 43 of the screw head is spaced from the bottom of the socket in the plug by an exceedingly 35 slight distance, possibly not exceeding one hundredth of an inch, and this is the extent of the adjustment provided for. The screw can only be advanced by a distance equal to the interval between its lower 40 face 43 and the bottom of the socket, and the follower can only be moved downward, and the effective length of the valve spindle or needle shortened by the same interval. This interval is predetermined by the manufacturer of an extent so that it is impossible to so throw the carbureter out of adjustment that it will not produce a running mixture.

The operation of the device will be apparent from the description taken in connection with the preamble. At low throttle with the engine running slowly, a sufficient supply of air is drawn in through the constant opening 4. This in passing 55 through the constricted opening 5 sucks up a supply of gasoline from the nozzle 6, the latter being closed to its minimum opening by the action of the cam 29, and the mixture thus formed passes the throttle valve 60 and into the engine. As the throttle is opened, the speed of the engine increases and incidentally, the suction of the engine and the vacuum in the mixing chamber 3 are increased and the valve 9 is opened to 65 an extent depending on the suction, and in

case the device for releasing the spring tension is used, the opening of the valve is increased by the release of the spring tension which is simultaneous with the opening of the throttle. As the auxiliary valve 9 70 opens, the cam 29 moves to the right, permitting the needle valve 25 to move upward in response to the pressure of the spring 42, the cam follower 30 engaging the cam surface 29, serving to determine 75 the position of the valve. Thus the needle valve opening is increased and the proportions of the mixture are maintained.

For the purpose of varying the supply of gasoline available to be taken up by the air 80 passing through the carbureter and in order to adjust the carbureter to comply with changing conditions, as that of season and variation in quality of the fuel used, the adjustment of the effective length of the 85 needle valve is provided. If it is found that the mixture is too weak, *i. e.*, if the temperature drops to a considerable extent or the fuel is less volatile than that to which the carbureter has been adjusted, the screw 90 34 may be rotated to advance it and change the position of the sliding block, shortening the effective length of the valve spindle. On the other hand, if the mixture is too rich, the temperature having risen and the 95 humidity decreased, or if it is desired to use more volatile fuel, the screw 34 is rotated in the opposite direction to withdraw it, permitting the block 39 to move oppositely increasing the effective length of the fuel 100 valve spindle.

The dealer may find it desirable to give the carbureter a perfect adjustment when it leaves his hands and lock the parts so the adjustment cannot be disturbed. To this 105 end, a cap 47 is supplied covering the adjusting screw and it is locked to the frame by means of a suitable lock 44 and cooperating brackets 45 and 46 having registering apertures to receive the lock.

As I have stated, the cam 29 to be used with the carbureter is determined by accurate tests for each model of engine with which the carbureter is to be used to give at all throttles and speeds the mixture which 115 operates most efficiently and hence, with the best economy, so that with any engine of a model for which carbureters of this kind have been previously supplied, it is only necessary to select a carbureter of the same 120 size and having a cam exactly similar to that determined by the test. This may be applied without question and will give the same efficiency in every instance, provided the engine is in good order.

I have thus described specifically and in detail a single embodiment of my invention in order that its nature and operation may be clearly understood; however, the terms herein are used in their descriptive rather 130

than in their specific or limiting sense and the scope of the invention is defined in the claims.

I claim—

- 5 1. In a constant level carbureter, a constant air opening, a fuel nozzle therein, a needle valve for controlling the flow of gasolene at the nozzle, an auxiliary air valve opening inward, each valve having a stem disposed in the direction of the motion of that valve, the lines of motion of the two stems intersecting, a cam carried by the auxiliary air valve stem, a follower on the fuel valve spindle, and means for adjusting the effective length of the fuel valve stem, *i. e.*, the distance between the seating surface of the valve and the follower.
- 10 2. In a constant level carbureter, a main air opening, a fuel nozzle therein, a needle valve for controlling the flow of gasolene at the nozzle, an auxiliary air valve opened by the suction, each valve having a stem extending in the direction of motion of that valve, the directions of the two stems intersecting, two coöperating members consisting of a cam and follower, one being rigidly connected to the auxiliary air valve stem, the other being carried by the fuel valve stem, and means for adjusting the effective length of the fuel valve spindle.
- 15 3. In a constant level carbureter, a main air opening, a fuel nozzle, a needle valve for controlling the flow of gasolene, an auxiliary air valve, each valve having a stem extending in the direction of motion of that valve, the directions of the two stems intersecting, opening inward, a constant tension, non-adjustable spring tending to maintain the auxiliary air valve closed, two coöperating members consisting of a cam and a follower, one being rigidly secured to the auxiliary air valve stem, and the other to the fuel valve stem.
- 20 4. In a carbureter, a main air opening, a fuel nozzle, a needle valve for controlling the flow of gasolene, an auxiliary air valve opening inward, each valve having a stem extending in the direction of motion of that valve, the directions of the two stems intersecting, a constant tension, non-adjustable spring tending to maintain the auxiliary air valve closed, two coöperating members consisting of a cam and follower, one being rigidly secured to the auxiliary air valve stem, and the other to the fuel valve spindle.
- 25 5. In a constant level carbureter, a main air opening, a fuel nozzle, a fuel valve for controlling the flow of gasolene, an auxiliary air valve, each valve having a stem extending in the direction of the valve opening, a constant tension, non-adjustable spring tending to maintain the auxiliary air valve closed, the latter opening inward in response to the suction of the engine, a cam fixed as to its outline and rigidly and non-adjustably secured to the auxiliary air valve, and a follower mounted on the fuel valve spindle engaging the cam.
- 30 6. In a carbureter, a main air opening, a fuel nozzle, a fuel valve for controlling the flow of gasolene, an auxiliary air valve, each valve having a stem extending in the direction of the valve opening, a constant tension, non-adjustable spring tending to maintain the auxiliary air valve closed, the latter opening inward in response to the suction of the engine, a cam fixed as to its outline and rigidly and non-adjustably secured to the auxiliary air valve, and a follower on the fuel valve spindle engaging the cam.
- 35 7. In a carbureter, a main air opening, a fuel nozzle, a fuel valve for controlling the flow of gasolene, an auxiliary air valve, each valve having a stem extending in the direction of the valve opening, a constant tension, non-adjustable spring tending to maintain the auxiliary air valve closed, the latter opening inward in response to the suction of the engine, a cam fixed as to its outline and rigidly and non-adjustably secured to the auxiliary air valve, and a follower on the fuel valve spindle engaging the cam.
- 40 8. In a constant level carbureter, a constant air opening, a fuel nozzle, a fuel valve for controlling the flow of gasolene, an auxiliary air valve opened by the suction, a spring tending to maintain the auxiliary air valve closed, a cam fixed as to its outline and rigidly and non-adjustably secured to the auxiliary air valve, a follower on the fuel valve spindle to engage the cam, means for adjusting the effective length of the fuel valve spindle and an abutment for the auxiliary air valve spring, a throttle valve and connections between the abutment and throttle valve whereby the tension of the spring is released as the throttle valve is opened.
- 45 9. In a carbureter, a normally automatically closed fluid pressure actuated reciprocable valve controlling an air-inlet port and having a stem projecting from the carbureter housing, a projection on said stem externally of said housing having an inclined face, a reciprocable valve controlling the supply of hydro-carbon liquid and having a stem provided with a longitudinal slot through which the stem of the air-inlet valve passes and through which said projection travels, a part of said stem of said valve controlling the liquid supply disposed in the path of the inclined face of said projection for transmitting movement of the first-named to the last-named valve.
- 50 10. In a carbureter, a normally automatically closed fluid-pressure actuated reciprocable valve controlling an air-inlet port and

adjusting the effective length of the fuel valve spindle in the form of a sliding block carrying the said member, a screw for determining the position of the block and a resilient member for maintaining the block in contact with the screw.

70 6. In a constant level carbureter, a main air opening, a fuel nozzle, a fuel valve for controlling the flow of gasolene, an auxiliary air valve, each valve having a stem extending in the direction of motion of that valve, the directions of the two stems intersecting, a spring tending to maintain the auxiliary air valve closed, the latter opening inward in response to the suction of the engine, a cam fixed as to its outline and rigidly and non-adjustably secured to the air valve stem, and a follower mounted on the fuel valve spindle engaging the cam.

75 7. In a carbureter, a main air opening, a fuel nozzle, a fuel valve for controlling the flow of gasolene, an auxiliary air valve, each valve having a stem extending in the direction of the valve opening, a constant tension, non-adjustable spring tending to maintain the auxiliary air valve closed, the latter opening inward in response to the suction of the engine, a cam fixed as to its outline and rigidly and non-adjustably secured to the auxiliary air valve, and a follower on the fuel valve spindle engaging the cam.

80 8. In a constant level carbureter, a constant air opening, a fuel nozzle, a fuel valve for controlling the flow of gasolene, an auxiliary air valve opened by the suction, a spring tending to maintain the auxiliary air valve closed, a cam fixed as to its outline and rigidly and non-adjustably secured to the auxiliary air valve, a follower on the fuel valve spindle to engage the cam, means for adjusting the effective length of the fuel valve spindle and an abutment for the auxiliary air valve spring, a throttle valve and connections between the abutment and throttle valve whereby the tension of the spring is released as the throttle valve is opened.

85 9. In a carbureter, a normally automatically closed fluid pressure actuated reciprocable valve controlling an air-inlet port and having a stem projecting from the carbureter housing, a projection on said stem externally of said housing having an inclined face, a reciprocable valve controlling the supply of hydro-carbon liquid and having a stem provided with a longitudinal slot through which the stem of the air-inlet valve passes and through which said projection travels, a part of said stem of said valve controlling the liquid supply disposed in the path of the inclined face of said projection for transmitting movement of the first-named to the last-named valve.

90 10. In a carbureter, a normally automatically closed fluid-pressure actuated reciprocable valve controlling an air-inlet port and
